UNITED STATES PATENT OFFICE.

ELBERT S. STEWART AND CALVIN G. RICE, OF PRATT, KANSAS; SAID STEWART ASSIGNOR TO SAID RICE.

PUMP.

SPECIFICATION forming part of Letters Patent No. 769,281, dated September 6, 1904.

Application filed May 14, 1904. Serial No. 207,991. (No model.)

To all whom it may concern:

Be it known that we, ELBERT S. STEWART and CALVIN G. RICE, both citizens of the United States, residing at Pratt, in the county of Pratt and State of Kansas, have invented certain new and useful Improvements in Pumps, of which the following is a specification.

Our invention relates to that class of pumps known as "lift-pumps," in which a valved piston reciprocates in a tube or casing, causing the water or other fluid to be raised from a great depth to the surface. In such pumps ordinarily the check-valve is located near the bottom of the tube and the piston, which is normally located a short distance above the check-valve, is reciprocated by a rod. The piston is provided with packing-rings, and as after a time these become worn and leaky it is desirable to remove the piston for repairs. It is difficult to accomplish this in such pumps as ordinarily constructed, because while the piston is being elevated its valve is closed, and there is therefore great resistance to the upward passage of the piston.

According to our invention we provide devices by means of which the piston-valve may be held open while the piston is being withdrawn from the tube.

In carrying out our invention we use a tube or casing of ordinary construction and in the lower portion thereof provide an ordinary check-valve. The piston is provided with a valve, preferably a puppet-valve, which is arranged in a frame or cage, by which it is guided and which as it moves up and down opens and closes communication between the spaces in the tube above and below the piston. Normally as the piston descends the valve is opened and water passes to the space above the piston, and when the piston is raised the valve closes and the water above the piston is raised and discharged at the top of the tube. In order to hold the piston-valve open while the piston is being withdrawn from the tube for repairs or for other purposes, we provide the piston with a rod adapted to support it. This rod is provided with spring-catches, connected with and supported on a part of the piston. The rod also

carries at its lower end a frame which is 50 adapted to move up and down in the lower portion of the piston. This frame projects below the piston and in the normal operation of the pump does not interfere in any way with the action thereof; but when the piston 55 is designedly lowered to a greater extent than usual the frame carrying the valve-supporting rod abuts against the frame of the check-valve and it is caused to rise in the piston and the spring-catches engage the piston 60 when the rod is raised and hold the rod in an elevated position against the piston-valve, which is then held up in such manner as to open a free communication between the bore of the tube both above and below the piston, 65 so that when the piston is raised out of the pump it may move without meeting with the usual resistance caused by the column of water above it.

In the accompanying drawings, Figure 1 70 shows a vertical central section of a portion of a lift-pump embodying our improvements with the parts in their normal operating position. Fig. 2 is a similar view with the piston-valve held open and in position to be raised 75 out of the pump.

The pump casing or tube A may be made in any suitable way and has a discharge-spout A'.

The check-valve B is of usual construction and may operate in the usual way. The piston is shown as being constructed with an upper frame C, forming a cage for the piston-valve D. This cage is connected with the valve-operating rod E, and it has a tubular guide c for the stem d of the puppet-valve 85 D and which is formed with lateral openings c' to prevent the accumulation of fluid within it. The large lower end of the upper casing C is provided with ports c'', to permit water to pass laterally from the inside of the piston 90 to the outside thereof.

To the casing C is attached a sleeve F, flanged at f and having between this flange and the lower flanged end of the casing C packing-rings G H I. The packing-rings fit the tube 95 or casing A snugly and prevent fluid from passing from one end of the piston to the other around the outside thereof. The sleeve F has

attached to its lower flanged end another sleeve, J, which projects downwardly therefrom and is formed with a cross-piece or guide *j*, through which extends a rod K, that also extends upwardly through a guide L in the sleeve F. To the lower end of the rod K is attached a frame or short cylinder M, having a cross-piece *m*, through which extend the legs *n* of the catch N. This catch is rigidly connected with the rod K and extends through openings in the cross-pieces *j* and *m*. When the parts are in the position shown in Fig. 1 for the normal operation of the pump, the upper end of the rod K is below the valve-seat D' and has no effect thereon. As the piston is reciprocated water is raised and discharged from the pump in the ordinary way. If, however, the piston is forced down to an unusual extent the frame or cylinder M will strike against the casing of the check-valve B and will be caused to rise in the piston and cause the rod K, which is rigidly connected with it, to abut against the pump-valve D and raise it to the position shown in Fig. 2. In doing this the catch N, which is carried by the rod K, is also raised and its shoulders *n'* pass through the cross-piece *j* and rest upon this cross-piece in the manner shown in Fig. 2. The rod K is thus supported in an elevated position and holds the pump-valve D open. If now the piston is raised, no water will be lifted, inasmuch as the pump-valve is held open, and therefore the piston can be easily withdrawn. Before returning the piston to its normal position the catch N should be readjusted so that the parts will assume the position shown in Fig. 1. They will remain in this position as long as desired and until the piston is lowered to an abnormal extent in order to shift the parts to the position shown in Fig. 2.

A pump thus constructed will be found to operate most efficiently, working as usual in ordinary operation and quickly acting to shift the parts to hold the pump-valve permanently open when it is desired to remove the piston for repairs or for other purposes.

We claim as our invention—

1. A pump comprising a tube or casing, a check-valve therein, a valved piston, a rod adapted to engage the valve, but held normally out of engagement therewith, a frame projecting from the lower end of the piston to which the rod is attached and which is adapted to move vertically toward and from the piston, and a catch comprising shouldered legs on opposite sides of the rod and carried by the rod and adapted to engage the piston and hold the rod in an elevated position against the piston-valve, for the purpose specified.
2. The combination of a tube or casing, a check-valve therein, a piston having a freely-

moving valve, a rod adapted to engage the piston-valve and hold it open but which is normally held out of engagement therewith, a rigid frame to which the rod is connected and which projects below the bottom of the piston, and a spring-catch carried by the rod having legs provided with shoulders for engaging the piston on opposite sides of the rod, and parts extending into the frame by which the catch can be operated, for the purpose specified.

3. The combination of a tube or casing, a check-valve therein, a piston-valve, a cage or casing within which it is located and by which it is guided, a sleeve detachably connected with this casing and having a guide within it, packing-rings interposed between the cage and this sleeve, another sleeve or cylinder detachably connected with said first-mentioned sleeve and having a guide within it, a rod extending through the guides within the sleeves, a frame or casing within the lower sleeve and guided thereby and which is attached to the lower end of said rod, and a spring-catch carried by the rod and adapted to engage the guide in one of said sleeves for the purpose specified.

4. A pump comprising a tube or casing, a check-valve therein, a piston within the tube above the check-valve comprising a cage, a puppet-valve moving freely therein and normally free to seat itself while the piston is being raised, a rod supported by the piston but normally held out of engagement with the puppet-valve, a catch carried by this rod and adapted to engage the piston but which is normally held out of engagement therewith, and a cylindrical frame guided vertically by the piston and attached to the rod for causing the catch to operate to hold the rod in an elevated position when the piston is lowered to an unusual extent.

5. A pump comprising a tube or casing, a check-valve therein, a valved piston, a cage or casing within which the valve is located and by which it is guided, sleeves attached to this cage and having cross-pieces provided with guides, a rod sliding in said guides, a cylindrical frame attached to the rod and guided by one of the sleeves, and a catch attached to the rod and adapted to engage the cross-pieces in the sleeves to hold the frame in either an elevated or a lowered position, for the purpose specified.

In testimony whereof we have hereunto subscribed our names.
